UNITED STATES PATENT OFFICE.

DESSIE L. GABLER, OF FOND DU LAC, WISCONSIN.

UMBRELLA.

1,243,153.

Specification of Letters Patent. Patented Oct. 16, 1917.

Application filed May 14, 1917. Serial No. 168,453.

To all whom it may concern:

Be it known that I, DESSIE L. GABLER, a citizen of the United States, residing at Fond du Lac, in the county of Fond du Lac 5 and State of Wisconsin, have invented certain new and useful Improvements in Umbrellas, of which the following is a specification, reference being had to the accompanying drawings.

10 This invention relates to an improved umbrella, and has for its primary object to provide an improved sectional, jointed umbrella staff, whereby the staff sections may be relatively positioned so that the umbrella cover will be centrally disposed over 15 the person carrying the umbrella.

It is also another object of the invention to provide a very simple joint connection 20 between the staff sections, and means for locking the joints against breaking so as to maintain the staff rigid when the umbrella is closed.

25 It is a further general object of my invention to improve and simplify the construction of umbrellas of the above character, whereby the same are rendered highly convenient and serviceable in practical use and capable of manufacture at small cost.

With the above and other objects in view, 30 my invention consists in the novel features of construction, combination and arrangement of parts to be hereinafter more fully described, claimed and illustrated in the accompanying drawing, in which,

35 Figure 1 is a side elevation of an umbrella provided with the present improvement and showing a portion of the umbrella cover broken away;

40 Fig. 2 is an enlarged side elevation of one of the joints, the staff sections being locked in alinement with each other;

Fig. 3 is a longitudinal sectional view, the joint being broken away;

45 Fig. 4 is a section taken on the line 4—4 of Fig. 3;

Fig. 5 is a detail perspective view of one of the joint members; and

Fig. 6 is a similar view of the locking sleeve.

50 Referring in detail to the drawing, 5 designates one of the end sections of the umbrella staff or rod to which the handle 6 is attached, 7 the other end section to which the ribs of the cover 8 are suitably connected, and 9 the intermediate staff section. 55 These several sections of the umbrella staff

are constructed of tubular material in the usual manner, and the end sections 5 and 7 are connected to the relatively opposite ends of the intermediate section 9 by means of 60 my improved joint, whereby the several staff sections may be angularly disposed with respect to each other as shown in Fig. 1, or extended and locked in longitudinally alined relation. The particular construction 65 of this joint connection between the staff sections I will now proceed to describe in detail.

Each of the staff joints includes the member 10, preferably formed of steel and provided with a diametrically reduced portion 11 upon which a locking sleeve 12 is loosely mounted to rotate. The member 10 is longitudinally slotted, as at 13, said slot opening 70 upon one end of said member and extending 75 into the reduced portion 11 thereof. The sleeve 12 is provided in one of its ends with a rectangular notch or recess 14 to coincide with the slot 13. The other end of the member 10 as shown at 15, is adapted for engagement 80 in the end of the tubular staff section and is riveted or otherwise permanently fixed thereto.

The other member 16 of the joint is in 85 the form of a flat, rectangular tongue 17 which projects from the cylindrical body of said member, said tongue being provided at its end and in its opposite longitudinal edges with the notches 18. The body of the member 16 is likewise provided with a reduced, cylindrical stem 19 to be fixed within the other section of the umbrella staff. The tongue 17 is disposed within the slot 13 of the joint member 10 and is loosely mounted 90 upon the pivot pin 20 traversing said slot and fixed at its ends in said joint member. The maximum width of the tongue 17 is equal to the diameter of the joint member 10, while the width of the reduced end 95 of said tongue is equal to the diameter of the reduced portion 11 of said joint member. It will thus be apparent that when the joint members are disposed in longitudinal alinement and the tongue 17 is within the slot 13, upon rotating the sleeve 12 100 in one direction, the notch 14 in the end thereof is moved out of registering relation to the slot 13, as shown in Fig. 1, and the member 16 is then held securely against pivotal movement with respect to the joint member 10. The opposite end of the locking sleeve 12 is provided with an elongated 110

recess having an inclined base wall 21. A pin 22 fixed in the joint member 10, is disposed in said recess, and by engagement with one end of the recess, limits the rotation of the locking sleeve into position to register the notch 14 therein with the slot 13. In moving the sleeve to its locking position, the inclined wall 21 rides upon the pin 22, thereby tending to shift the locking 10 sleeve longitudinally, and by such frictional co-action with the pin, preventing the casual turning movement of the sleeve from its locking position. The sleeve 12 is also provided in its end, in diametrically opposed 15 relation to the notch 14, with a shallow recess 23, the base wall of which merges into the end edge of the sleeve to provide a cam surface 24. Thus, after the joint has been broken, the rotation of the sleeve is reversed, 20 and this cam surface 24 bearing against the joint member 16 rocks said member upon its pivot and causes the edge of the tongue 17 to bear tightly against the end of the locking sleeve. Thus, the staff sections will 25 be rigidly held in their angular positions against relative movement.

From the foregoing description, taken in connection with the accompanying drawing, the construction, manner of operation, and 30 several advantages of the device will be clearly and fully understood. By positioning the several sections of the umbrella staff as seen in Fig. 1 of the drawing, the umbrella may be carried with the staff sections 35 7 disposed immediately above the head of the user so that the water will not drip from the outer edge of the cover upon the back and arms, as is the case with the ordinary umbrella where the staff is in one, 40 continuous section. When the sections of the joint are locked in alinement, their peripheral faces are flush with the peripheral surfaces of the staff sections so that the runner to which the stretcher ribs are connected 45 may move freely over the joints. The device as a whole is of exceedingly simple construction and may be readily applied to the ordinary umbrella in the manufacture thereof at but slightly increased cost. The

device is also very durable and of great convenience and serviceability in practical use. 50

While I have herein shown and described the preferred construction and arrangement of the several elements employed, it is to be understood that the same are susceptible of 55 considerable modification therein and I, therefore, reserve the privilege of adopting all such legitimate changes as may be fairly embodied within the spirit and scope of the invention as claimed. 60

Having thus fully described my invention, what I desire to claim and secure by Letters Patent is:

1. A joint of the character described including two pivotally connected members, a 65 rotatable locking sleeve mounted upon one of said members and having means which, in one position of the sleeve, permits of the angular movement of the other joint member, said sleeve also having additional means 70 to co-act with the latter joint member when the sleeve is rotated in one direction to securely lock said joint member in its angular position to the first joint member.

2. A joint of the character described in- 75 cluding a joint member having a longitudinal slot therein opening upon one end of said member, a second member having a tongue pivotally mounted in said slot, a ro- 80 tatable locking sleeve mounted upon the first joint member, said sleeve having a recess in one end adapted to coincide with said slot to permit of the angular movement of the second joint member, and means for limit- 85 ing the rotation of the sleeve to such position, said sleeve being also provided with additional means to co-act with the second joint member when the sleeve is rotated to locking position to rigidly hold said second joint member against movement from its 90 angular position with respect to the first joint member.

In testimony whereof I hereunto affix my signature in the presence of two witnesses.

DESSIE L. GABLER.
